UNITED STATES PATENT OFFICE.

JOHN J. BOWES, JR., OF PENSACOLA, FLORIDA.

TUBE-COMPRESSOR.

1,347,931.

Specification of Letters Patent.

Patented July 27, 1920.

Application filed August 15, 1919. Serial No. 317,773.

To all whom it may concern:

Be it known that I, JOHN J. BOWES, Jr., a citizen of the United States, and a resident of Pensacola, in the county of Escambia 5 and State of Florida, have invented certain new and useful Improvements in Tube-Compressors, of which the following is a specification.

My invention is an improvement in tube 10 compressors, and has for its object to provide a device of the character specified, adapted for compressing a flexible tube to prevent the flow of liquid therethrough, as for instance the tube of a syringe, wherein 15 the arrangement is such that the tube will be efficiently clamped shut, assuring a water tight closure, without undue wear on the tube.

A further object is to provide mechanism 20 in connection with the compressor for permitting the pressure to be relaxed to permit a limited flow, as for instance in the Murphy drip treatment.

In the drawings:

25 Figure 1 is a plan view of the blank from which the improved compressor is formed,

Fig. 2 is a side view showing the compressor closed on a tube,

Fig. 3 is a side view of the clamp open,

30 Fig. 4 is a top plan view of the compressor,

Figs. 5 and 6 are plan and side views respectively of the lower gripping jaw,

Figs. 7 and 8 are top plan and side views 35 of the controlling lever.

In the present embodiment of the invention the improved compressor is formed from a blank like that shown in Fig. 1. This blank as shown is composed of a ring 1 having radial extensions 2 and 3, extending in opposite directions from the ring and the extension 2 has pairs of lugs 4 and 5, the members of each pair extending in opposite directions from the edges of the extension, 40 the lugs 5 being perforated. The extension 3 has a pair of lugs 6, the members of the pair extending in opposite direction from the extension as shown, the lugs being similar, and each having its outer edge 7 serrated to 45 form ratchet teeth.

The blank is bent so that the extensions 2 and 3 overlie each other in spaced parallel relation, with the opening through the ring 1 in position to receive the tube 8 to be compressed when the said tube is passed between the extensions 2 and 3. The lugs 6 are

bent toward the extension 2, to lie on opposite sides thereof, and the lugs 5 of the extension 2 are bent away from the extension 3, to provide a pivotal mounting for a finger-piece 9.

As shown in Figs. 7 and 8 this finger-piece has oppositely extending lugs 10 which are pivoted in the openings of the lugs 5, and it has other lugs 11 which are adapted 60 to engage the ratchet teeth 7 of the lugs 6, to hold the finger-piece in adjusted position. The finger-piece is also provided with a plate spring 12, secured thereto at one end, the other end of the spring engaging the extension 2 to normally hold the lugs 11 in engagement with the ratchet teeth.

This extension 2 has a transverse rib 13 intermediate its ends, and on the face adjacent to the tube 8, and at the lugs 4, and 65 it is this rib that engages the tube to clamp the same. A gripping jaw 14 is connected to the extension 3 near its junction with the ring 1, the said jaw having a pin 15 which engages an opening in the extension 3, and 70 the opposite end of the jaw has a cross head 16 which is curved as shown in Fig. 6, in the opposite direction to the rib 13, and this curve or rib 16 co-operates with the rib 13 to grip the tube 8. A set screw 17 is threaded 75 through the extension 3, and engages the jaw 14 at its inner end. By means of the set screw pressure of the jaw 16 on the tube may be nicely regulated. With the parts in the position of Fig. 2, it will be obvious 80 that by loosening the set screw a slight opening of the tube may be brought about and this opening may be made to any extent desired.

In use the compressor is arranged upon 95 the tube as shown in Fig. 2, with the tube extending through the opening of the ring 1. The extensions 2 and 3 are at this time in the position shown in Fig. 3, that is the lugs 11 which are bent outwardly as shown 100 in Fig. 8 are disengaged from the ratchet teeth, and the extension 2 is at its farthest point from the extension 3, the upward movement of the extension being limited by struck-up spurs 18 on the lug 6. To compress the tube, the extensions 2 and 3 are moved toward each other. In order to move them toward each other they may be grasped between the thumb and finger at their free ends. As they are moved toward each other, 105 the lugs 11 will slip idly over the ratchet teeth, but will hold the extensions from

movement away from each other. In order to permit a drip of fluid from the tube, that is a limited flow, the set screw 17 may be turned to relax the pressure of the jaw 14.

5 I claim:

1. A device of the character specified, comprising a strip doubled upon itself to lie on opposite sides of a tube at its ends and having a central opening for receiving the tube, one of the ends having ratchet teeth and the other a spring controlled latch engaging the teeth for holding the said ends clamped on the tube, the other of the said ends having an auxiliary gripping jaw on

the inner face thereof for directly engaging 15 the tube, and a set screw threaded through the said end and engaging the jaw for the purpose specified.

2. A device of the character specified, comprising a pair of gripping jaws spring 20 pressed away from each other, means in connection with the jaws for clamping said jaws against movement away from each other, one of said jaws having an auxiliary gripping member adjustable toward and 25 from the other jaw.

JOHN J. BOWES, Jr.
